(57) **CLAIM**

The ornamental design for a ladder top, as shown and described.

DESCRIPTION

FIG. 1 is a front perspective view of a ladder top showing our new design;

FIG. 2 is a rear perspective view of a ladder top showing our new design;

FIG. 3 is a top elevational view thereof;

FIG. 4 is a rear elevational view thereof;

FIG. 5 is a bottom elevational view thereof;

FIG. 6 is a front elevational view thereof;

FIG. 7 is a right side elevational view thereof; and,

FIG. 8 is a left side elevational view thereof.

The broken lines shown in the figures are included for the purpose of illustrating portions of the ladder top and form no part of the claimed design.

1 Claim, 7 Drawing Sheets
